STEEL TAPE AND WIRE PULLER

Michael J. Jaques, 602 S. Hobson, Mesa, Ariz. 85204

Filed Apr. 18, 1974, Ser. No. 461,858

Term of patent 14 years

Int. Cl. D8—05

U.S. Cl. D8—14

FIG. 1 is a perspective view of a steel tape and wire puller showing my new design;

FIG. 2 is a partial perspective side view from the opposite side shown in FIG. 1 with the metallic collar omitted at the end of the twisted wire since its shape is obvious from FIG. 1;

FIG. 3 is an enlarged partial side view of the steel tape and wire puller more clearly showing the swivel joint; and

FIG. 4 is an enlarged partial view of the steel tape and wire puller's end with a steel tape shown in dotted lines to illustrate the utility of the structure and the way the strands of the cord are untwisted in order to lay the steel tape therebetween.

I claim:

The ornamental design for a steel tape and wire puller, as shown and described.
